Patented July 12, 1921.

Application filed October 19, 1920. Serial No. 418,112. Term of patent 7 years.

To all whom it may concern:

Be it known that I, LUCY GRANT UNMACK, a citizen of the United States, residing at Los Angeles, in the county of Los Angeles and State of California, have invented a new, original, and ornamental Design for Lamps, of which the following is a specification, reference being had to the accompanying drawing, in which—

Figure 1 is a perspective view of the lamp as seen from the front thereof.

Fig. 2 is a perspective view as seen from the rear.

The characteristic feature of my design

resides in forming a lamp standard having the figure of a doll garbed in Japanese costume and which may be decorated with various articles of ornamentation, such as beads, ribbons, braid, and other trimmings to give the figure an oriental appearance in general and a Japanese effect in particular. The lamp is further characterized by employing a shade of Japanese design, substantially as shown.

I claim:

The ornamental design for a lamp substantially as shown and described.

LUCY GRANT UNMACK.
